United States Patent Office.

SAMUEL MADDEN, OF EUREKA SOUTH, CALIFORNIA.

Letters Patent No. 82,966, dated October 13, 1868.

IMPROVED CAR-COUPING.

The Schedule referred to in these Letters Patent and making part of the same.

To all whom it may concern:

Be it known that I, SAMUEL MADDEN, of Eureka South, county of Nevada, State of California, have invented an Improved Car-Coupling; and I do hereby declare the following description and accompanying drawings are sufficient to enable any person skilled in the art or science to which it most nearly appertains to make and use my said invention or improvements without further invention or experiment.

The nature of my invention is to provide an improved coupling for rail-cars, so constructed as to be self-acting, and avoid the danger of being caught between the cars while connecting them for the purpose of making up a train.

To accomplish this object, the bumper is rigidly attached to the end of the car, and has a flaring oval-shaped link-chamber, above which is placed a secondary bumper, moving in a slide, back of which is a spiral spring, which causes it to project beyond the lower bumper. Two longitudinal slots are made in the sliding bumper, which moves back and forth without disturbing the pin. The pin passes through the sliding bumper, and is provided with two collars, between which the sides of the slot moves; the upper collar, when the pin is raised, being at the top, and when the movable bumper is forced back in coupling, the pin falls down, passing through the vertical opening in the lower part of the stationary bumper. The link is provided with friction-rollers at each end, so that, as it enters the chamber of the bumper, it will always be right side up.

To more fully explain my invention, reference is had to the drawings accompanying this specification, and the letters marked thereon, of which—

Figure 1 is a side sectional view of my invention.

Figure 2 is a plan.

Similar letters of reference indicate corresponding parts in each of the figures.

A is the stationary bumper, having a flaring oval-shaped chamber. B. Vertical holes, C C, for the pin, are made near the end. The links are constructed somewhat similar to the ordinary link, and have friction-rollers, D, at each end, so that, as it enters the oval-shaped chamber of the stationary bumper, it will

always be flatwise, or right side up, for receiving the pin.

A movable bumper, E, is placed above the stationary bumper, which slides back and forth on ways. Back of this bumper is attached a spiral or other spring, F, which receives the force when the cars are thrown together, carrying the movable bumper back to near the end of the stationary one, and when released it projects beyond the stationary or link-bumper.

Longitudinal slots, G G', are made in the sliding bumper, and when the pin is elevated, the sides of the slot G move between the collars H H' of the pin I; and when the movable bumper is forced back sufficiently by the action of the succeeding car, the pin drops down into an opening, J, at the end of the slot, through the stationary bumper and link, and the car is coupled, the lower collar, H, of the pin resting on the top of the stationary bumper. The pin is prevented from moving laterally by a stationary plate, K, attached to the front of the car above the movable bumper. Thus the whole train may be made to self-couple.

The train may be uncoupled by raising the pin, even if the movable bumper is not forced entirely back, but the pin cannot be raised to the top of the sliding bumper until it is crowded back sufficiently to admit of the upper collar of the pin being raised through the opening at the end of the slot.

Having thus described my invention,

What I claim, and desire to secure by Letters Patent, is—

The above-described combination and arrangement of devices to form an automatic car-coupling, consisting of the sliding bumper E, with the slots G and G', opening J, and spring F, the pin I, with collars H and H', and the guiding-plate K, with or without the rollers D at the end of the link, substantially as specified.

In witness whereof, I have hereunto set my hand and seal.

SAMUEL MADDEN. [L. S.]
